J. T. DRUFVA,
PORTABLE ELECTRIC LIGHT,
APPLICATION FILED APR. 4, 1918.

1,287,262.

Patented Dec. 10, 1918.

UNITED STATES PATENT OFFICE.

JOHN T. DRUFVA, OF LONGMEADOW, MASSACHUSETTS, ASSIGNOR TO HENRY HYMAN & CO., INC., OF NEW YORK, N. Y., A CORPORATION OF NEW YORK.

PORTABLE ELECTRIC LIGHT.

1,287,262.

Specification of Letters Patent. Patented Dec. 10, 1918.

Application filed April 4, 1918. Serial No. 226,583.

To all whom it may concern:

Be it known that I, JOHN T. DRUFVA, a citizen of the United States, and a resident of Longmeadow, in the county of Hampden and State of Massachusetts, have invented certain new and useful Improvements in Portable Electric Lights, of which the following is a specification.

The invention pertains more particularly to the character of electric flash lights to be held in the hand and lighted, as occasion may require, by the manual movement of a slide applied upon the exterior casing of the device.

15 My present invention resides more especially in a novel arrangement and construction of parts, including a slide for completing the circuit between the lamp and battery and also a push button or the like which may be utilized independently of the slide for completing the circuit and flashing the light, the whole being arranged to obviate the accidental short circuiting of the lamp by contact with metal articles, such as might arise 25 when a flash light, otherwise constructed, is placed in a box of tools.

The flash light of my invention comprises an exterior casing, preferably of insulating material, a plural cell battery therein, a thumb piece or slide on a housing or escutcheon secured on the side of the casing, a spring circuit blade or strip contained within said housing and secured to said thumb piece or slide, conducting strips within said casing 35 leading respectively to the positive and negative poles of the battery, and a push button mounted in said housing or escutcheon and adapted independently of said thumb piece or slide to complete the circuit through the 40 lamp and battery, the thumb piece or slide being employed when a more or less permanent light is required, and the push button being made use of when it is desired to produce light flashes, as for signaling.

45 My invention resides more particularly in the novel means for completing the circuit through the lamp and battery, one contact spring operable either by the exterior slide or thumb piece or by the push button 50 being adapted to complete such circuit in accordance with the character of light desired to be produced.

The invention will be fully understood from the detailed description hereinafter

presented, reference being had to the accompanying drawings, in which:

Figure 1 is a central longitudinal section, with the wrapping on the battery partly broken away, of a portable flash light embodying the invention, the casing of the flash light being shown in this instance as a fiber tube;

Fig. 2 is a central vertical section through the tubular portion of the flash light, taken on the dotted line 2—2 of Fig. 1;

Fig. 3 is a detached inner face view of the housing or escutcheon applied to the exterior casing and containing the circuit making and breaking conducting spring;

Fig. 4 is a transverse section through the same and a portion of the exterior casing of the flash light, taken on the dotted line 4—4 of Fig. 3;

Fig. 5 is a similar section of the same, taken on the dotted line 5—5 of Fig. 3, and

Fig. 6 is a detached perspective view on a larger scale of the circuit making and breaking spring removed from the exterior housing or escutcheon present on the casing of the flash light.

In the drawings, 10 designates a tubular fiber or other insulating casing, 11 a plural cell battery therein, 12 a wrapping of insulating material on said battery, 13 a screw-cap of customary construction closing the lower end of said casing and engaging a metal sleeve 14 thereon, 15 a conducting spring compressed between the negative pole of the battery and the inner surface of said cap, 16 a sleeve screwed upon a sleeve 17 fastened upon the outer end of said casing, 18 a customary lens held by said sleeve 16, 19 a reflector within the outer end of the casing 10 and 20 an electric bulb of known character having its terminal sleeve 21 screwed into the usual threaded sleeve 22 at the inner end of said reflector, the other terminal 23 of the lamp being held in engagement with the positive pole 24 of the battery by means of the spring 15.

Within the casing 10 are two normally separated conducting strips 25, 26, the lower end of the strip 26 being in electrical connection with the negative pole of the battery, as usual, and the upper end of the strip 25 being carried upwardly to the upper edge of the casing 10 and in electrical connection with the reflector 19. The inner end of the

strip 26 is secured to one wing of a metal escutcheon or housing 27 by an eyelet 28, which aids in securing the escutcheon upon the side of the casing 10, and said strip 26 is therefore in electrical connection with said escutcheon or housing. The inner end of the strip 25 is secured to the casing 10 by means of an eyelet 29 whose outer end is exposed within the escutcheon or housing 27 but is not normally in electrical connection therewith. The housing is rigidly secured in position upon the casing 10 by the aforesaid eyelet 28 and an additional eyelet 30. Upon the exterior flat face of the escutcheon or housing 27 is mounted a thumb-piece or slide 31 preferably formed from sheet metal and having, at opposite sides, tongues 32 which are inserted through slots in the escutcheon or housing 27 and bent toward each other, not only to secure the thumb-piece or slide in position, but also to embrace one portion of a conducting spring 33 which is confined within the escutcheon or housing 27 and recessed at opposite edges, as at 34, to admit the inner ends of the tongues 32. The spring 33 is, by means of the inwardly bent inner ends of the tongues 32, clamped against the inner face of the escutcheon or housing 27 but is movable with the thumb-piece or slide 31. The spring 33 is utilized to complete the circuit through the lamp and battery when moved into engagement with the eyelet 29, said spring normally being free of said eyelet, although at all times having its forward end over said eyelet. The spring 33 is of special construction, having a body portion 35 which lies flat against the inner wall of the escutcheon or housing 27, and an inner return or bent portion 36 which is over the eyelet 29 and possesses a shoulder 37 and a foot portion 38 which engages and may ride along the casing 10; and said portion 36 is preferably slightly spaced from the adjacent surface of the body 35 of the spring 33. The spring 33 has a direct sliding movement when actuated by the thumb-piece 31, and when moved forwardly the shoulder 37 thereon engages the eyelet 29 and completes the circuit. The spring 33 is yieldingly locked in its normal inoperative and in its operative positions by means of a small stud 39 projecting inwardly from the escutcheon or housing 27 and adapted to receive one or the other of the two holes 40, 41 formed in the lower end of the spring 33. In Fig. 3 I illustrate the hole 40 as being engaged by the stud 39, and when the thumb-piece 31 and spring 33 are slid forwardly, the hole 40 will be sprung from over the stud 39, and when the hole 41 reaches said stud it will snap upon the same. The lower end of the spring 33 is free to have limited spring movement toward and from the adjacent surfaces of the escutcheon or housing 27, and said end of the spring 33 having

the holes 40, 41 cooperates with the stud 39 in forming a spring latch for yieldingly locking the spring 33 in either of its two positions.

The housing or escutcheon 27 is formed with an aperture 42 in which is movably mounted a push-button 43 whose inner edge is flanged so as to prevent the push-button from escaping from the escutcheon or housing 27, as shown in Fig. 1, and said edge of said push-button is against the upper end of the body of the spring 33. The upper portion of the spring 33 is always over or in line with the stud 29, and hence the push-button 43 may be employed to press the spring against the stud 29 for completing the circuit. The push-button 43 will be made use of when it is desired to flash the light, as in giving signals, whereas the slide or thumb-piece 31 will be employed to move the spring 33 into engagement with the stud 29 when it is desired to have a more or less permanent or steady light. The one spring 33 cooperates with both the thumb-piece or slide 31 and the push-button 43, so that the user of the device may at his option flash the light or have a permanent light.

The upper end of the conducting strip 25 is not in electrical connection with the sleeves 16, 17, and the upper portion of said strip is preferably secured to the casing 10 by an eyelet 44 whose outer portion is counter-sunk within the material of the casing 10, so as to be free of the sleeve 17.

The operation of the portable electrical light hereinbefore described will be understood without further detailed explanation. The purpose of the invention is to provide a flash light whose circuit will not be completed, except on the movement of the slide 31 or push-button 43, and the invention resides in the means for making and breaking the circuit, the other features of the flash light being of usual construction.

What I claim as my invention and desire to secure by Letters-Patent, is:

1. A circuit switch-mechanism for portable electric lights comprising, in combination, a metal escutcheon having a thumb-piece slidably mounted on its outer face and a spring slidably mounted on its inner face and connected with said thumb-piece to slide therewith to circuit closing position, and a push-button mounted in said escutcheon independently of said thumb-piece and spring and in line with the free end of said spring and adapted when manually pressed inwardly to engage said end of said spring and flex the spring to circuit closing position, said spring always being in position to be independently flexed by said push-button or slid by said thumb-piece, as occasion may require, to complete the circuit.

2. A circuit switch-mechanism for portable electric lights comprising, in combina-

tion, a metal escutcheon having a thumb-piece slidably mounted on its outer face and a spring slidably mounted on its inner face and connected with said thumb-piece to slide therewith to circuit closing position, and a push-button mounted in said escutcheon independently of said thumb-piece and spring and in line with the free end of said spring and adapted when manually pressed inwardly to engage said end of said spring and flex the spring to circuit closing position, said spring always being in position to be independently flexed by said push-button or slid by said thumb-piece, as occasion may require, to complete the circuit, and said escutcheon having a hole in which said push-button is freely movable and said push-button having at its inner edge a flange to prevent its escape outwardly from said hole.

3. A circuit switch-mechanism for portable electric lights comprising, in combination, a metal escutcheon having a thumb-piece slidably mounted on its outer face and a spring slidably mounted on its inner face and connected with said thumb-piece to slide therewith to circuit closing position, and a push-button mounted in said escutcheon independently of said thumb-piece and spring and in line with the free end of said spring and adapted when manually pressed inwardly to engage said end of said spring and flex the spring to circuit closing position, said spring always being in position to be independently flexed by said push-button or slid by said thumb-piece, as occasion may require, to complete the circuit, and said escutcheon having parallel guide slots in its outer face and said thumb-piece having side fingers extending inwardly through said slots and folded toward each other upon said spring for securing the same against the inner surface of the escutcheon, and said spring having recesses in its opposite edges to receive and interlock the spring with said fingers.

4. A circuit switch mechanism for portable electric lights comprising, in combination, a metal escutcheon having a thumb-piece slidably mounted on its outer face and a spring strip within said escutcheon and connected with said thumb-piece to slide therewith to circuit closing position and a push-button mounted in said escutcheon independently of said thumb-piece and in line with the free end of said spring and adapted when manually pressed inwardly to flex

the spring to circuit closing position, said spring always being in position to be independently flexed by said push-button or slid by said thumb-piece, as occasion may require, to complete the circuit, and said spring having a body portion and a return inwardly bent portion having a shoulder to electrically connect with a circuit conductor, and said return bent portion being normally slightly separated from the body of said spring.

5. A circuit switch mechanism for portable electric lights comprising, in combination, a metal escutcheon having a thumb-piece slidably mounted on its outer face and a spring slidably mounted on its inner face and connected with said thumb-piece to slide therewith to circuit closing position, a push-button mounted in said escutcheon independently of said thumb-piece and in line with the free end of said spring and adapted when manually pressed inwardly to engage and flex the spring to circuit closing position, said spring being in position to be independently flexed by said push-button or slid by said thumb-piece, as occasion may require, to complete the circuit, and means for yieldingly locking said spring in its inoperative and operative positions, comprising a stud extending inwardly from said escutcheon, and holes provided in said spring to engage said stud in the respective positions of said spring.

6. A circuit switch mechanism for portable electric lights comprising, in combination, an escutcheon having a thumb-piece slidably mounted on its outer face and a spring slidably mounted within the escutcheon and connected to said thumb-piece to slide therewith to circuit closing position, and a push-button mounted in said escutcheon independently of said thumb-piece and in line with the free end of said spring and adapted when manually pressed inwardly to flex the spring to circuit closing position, said spring always being in position to be independently flexed by said push-button or slid by said thumb-piece, as occasion may require, to complete the circuit.

Signed at Springfield, in the county of Hampden, and State of Massachusetts, this 2nd day of April, A. D. 1918.

JOHN T. DRUFVA.
